ELECTRIC TOY TRACKAGE

Original Filed Sept. 18, 1926

INVENTOR
L. Gessford Handy
BY Malton Harrison
ATTORNEY

UNITED STATES PATENT OFFICE

LEVIN GESSFORD HANDY, OF MOUNTAIN VIEW, NEW JERSEY

ELECTRIC TOY TRACKAGE

Original application filed September 18, 1926, Serial No. 136,359, now Patent No. 1,753,147, dated April 1, 1930. Divided and this application filed March 31, 1930, Serial No. 440,246. Renewed October 29, 1931.

This invention relates to trackage for toy electric trains, such for instance as is contained in my Patent No. 1,636,416, July 19th, 1927, and in my co-pending application 5 Serial No. 136,359, filed September 18, 1926, now Patent No. 1,753,147, dated April 1, 1930, the present application being a division of said mentioned co-pending application.

10 An object of the present invention is to provide improved means whereby the passage of a train over a given section or sections of the track may be made to control the operation of auxiliary devices such as 15 signals and the like.

A further object is to provide an electric toy track section intended to be attached to or removed from track forming relation with other electric toy track sections in the 20 usual manner, said section being constructed to include improved means whereby the passage of a train over said section will complete a shunt circuit, in parallel with the train circuit, for controlling one or more auxiliary devices.

25 A further object is to so construct the electric toy section that it will include a device arranged to be operated by a passing train for controlling a shunt circuit in parallel with the train circuit.

30 A more detailed object is to so construct the electric toy section that it will include a part arranged to be moved by being engaged by the flange of a passing car wheel for controlling an electric circuit including a signal device, the third rail and one of the wheel bearing rails of the electric toy section.

35 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

40 In the accompanying drawing which is to be taken as a part of this specification, and in which I have shown merely a preferred form of embodiment of the invention:—

Fig. 1 is a diagrammatic plan view of an electric toy track system illustrating the present invention associated therewith.

Fig. 2 is a top plan view of one of the 55 electric toy track sections of which the system Fig. 1 is built, said section being constructed in accordance with the present invention.

Fig. 3 is an enlarged transverse sectional view taken upon the plane of line III—III 60 of Fig. 2, and

Fig. 4 is a diagrammatic sectional view corresponding with a portion of Fig. 3 but illustrating a modified arrangement of contact parts. 65

Fig. 5 is a view similar to Fig. 4 but illustrating a further modified arrangement of contact parts.

Referring to the drawing for describing in detail the structure illustrated therein, the 70 reference characters L and G indicate the two metallic wheel bearing rails of an electric toy track section, and the reference character H indicates the intermediate or “third” metallic rail of said section. These 75 three separate rails are connected together by cross tie means, such as the three metallic cross ties 1, 2 and 3 as illustrated.

The intermediate or “third” rail is insulated from the other rails and from the cross ties by insulating members 4—4—4 as is customary. 80

The wheel bearing rails L and G as shown 85 are not insulated from the cross ties. They are held in metallic contact with said cross ties as by means of the tangs 5—5 provided upon the cross ties for this purpose and hence are in constant electrical connection with said cross ties.

90 Each of the rails L, G and H is provided with connecting means at its opposite ends by which it may be readily mechanically and electrically connected in track forming relation with aligned rails of adjacent other toy track sections. As an illustration of means for this purpose the drawing herewith shows said rails to be formed with sockets at their 95 ends and metallic pins 6—6 for engaging in said sockets, said pins being adapted to extend into similar sockets provided in the 100

aligned rails of adjacent other toy track sections.

The track system illustrated in Fig. 1 is made up of a series of toy electric track sections constructed as thus described, said sections being connected together end to end in a well known manner. A source of electrical energy is indicated at 7 with a conductor 8 leading from one side thereof to the "third" rail of the system, and with a conductor as 9 from its opposite side connected with the two wheel bearing rails of the system, it being noted that although the conductor 9 is shown in Fig. 1 as having direct connection with both of the wheel bearing rails it is usually sufficient to connect said conductor directly with only one of said rails, the current being fed to the other wheel bearing rail through the several metallic cross ties which provide a metallic bond between the wheel bearing rails as above explained.

In Fig. 1 a signal device to be operated by a passing train is indicated at 10, and an electric toy section constructed in accordance with the present invention is shown at 11. A conductor 12 extends from a part of the section 11 to the signal 10 and a second conductor, as 13, connects the opposite side of the signal device with the wheel bearing rail G of the section.

A train is indicated as travelling along the system said train having wheels 14 riding upon the wheel bearing rails L and G and having a contact shoe 15 riding upon the "third" rail, the shoe being connected to one side of a train propelling motor 16, the opposite side of the motor being mounted upon the frame as 17 of the train and hence upon all of the wheels of the train and upon the wheel bearing rails L and G.

The propelling circuit for the train is of the usual type well known in this art, namely, from source 7 through conductor 8 to the "third", or power, rail, through the shoe 15 and motor 16 to ground upon the frame of the train and back to the opposite side of the source through the wheel bearing or "ground" rails L and G.

A shunt circuit through the signal device 10 is closed as soon as one of the wheels of the train rides into engagement with the portion 11 of the present attachment, said shunt circuit being in parallel with the train circuit as follows: From source 7 along the "third" rail to the contact device 18 through said contact device and along conductor 12 to the signal device 10 and back by way of conductor 13 to the wheel bearing rail G and thence by way of said wheel bearing rail back to the opposite side of the source.

The detailed construction and arrangement of parts of the present improved section including the contact device 18 may now be readily understood as follows: The portion 17 is a strip of insulating material which

extends longitudinally of the toy section closely adjacent one of the wheel bearing rails for instance the rail G, being in position to be engaged by the flange as 19 of one of the wheels 14 of the train. It is carried upon one or more spring arms as 20—20 and is adapted to be depressed by the wheel flange from the position indicated in full lines to the position indicated in dotted lines in Fig. 3. One or both of the spring arms 20 is electrically connected with the "third" rail H being preferably soldered thereto as indicated at 21 and when the member 17 is depressed by the car wheel flange it carries a portion of the spring arm or arms downwardly into electrical engagement with a contact as 22. The contact 22 is mounted upon an insulating base as 23. Where two spring arms are employed, as indicated in the drawing the contact 22 may consist of a strip of metal extending longitudinally of the toy section from one of said spring arms to the other and there may be two of the insulating base pieces 23 for its support.

Two binding posts as 24 and 25 are provided mounted upon one of the insulating pieces, the post 24 being connected with one of the wheel bearing rails as for instance the rail G, as by a conductor 26 and the post 25 being connected with the contact member or members 22 by means of a conductor 27.

It will be apparent from this description of detail that as soon as a car wheel traversing rail G moves onto the insulating strip 17 it will depress said strip so as to complete an electrical connection between the "third", or power, rail H and the contact 22, and of course outwardly from said contact by way of conductor 27 binding post 25 and conductor 12 to the signal or like device 10 and back through conductor 13 binding post 24 and conductor 12 to the rail G. This circuit will continue as long as the car wheel remains upon the strip 17 but will be broken again as soon as the strip 17 is free to spring back to its normal position.

The contact 22 is preferably of a resilient character so that it will be adapted to yield to a greater or less extent when pressed against by the upper contacts, that is by the spring fingers 20.

In the modification Fig. 4 the structure is substantially the same as above described except that in this instance a contact spring arm as 28 is provided in lieu of the contact parts heretofore described and arranged to be pressed directly against the rail G by the weight of the passing car wheel. A conductor as 29 leads from this spring arm to one of the binding posts, and a second conductor as 30 provides electrical connection between the "third" rail and the other binding post. When a train passes over this structure the weight of the car pressing against the contact 28 will move said contact into engage-

ment with the rail G and the shunt circuit will extend from rail H along conductor 30 to the signal device and back along conductor 29 to the contact 28 and into rail G. It may be noted that actual contact of the member 28 with the rail G is not essential since said member 28 will be in engagement with the car wheel and through said wheel to ground on the train and thence into either or both of the wheel bearing rails and back to the source as heretofore. The insulating support or base 23 in this structure, as well as in the structure Figs. 1 to 3, extends to engage the rails G and H and to thereby utilize both of these rails in holding itself and the contact parts in proper relation to said rails and to the car parts moving along said rails. The insulating support serves in effect as a spacer between the rails and parts of opposite polarity, so that no electrical connection or short circuit can at any time occur between said rails and said parts of opposite polarity.

In the modification Fig. 5 the structure is similar to that illustrated in Fig. 4 except that in this instance the contact spring arm or strip as 31 is connected directly with the track rail G instead of being carried by separate insulating base or carrying plate 23. Suitable insulation, as 32, is provided between the strip and the rail and said insulation and strip are firmly fixed to the rail so that the strip is carried by said rail as a part thereof in insulated relation thereto. The upper part of the strip 31 is formed to provide a portion as 33 directly overlying the upper surface of the rail. A passing car wheel will ride upon the upper surface of portion 33 and will thus make electrical contact therewith.

If desired the material of the strip 31 may be suitably resilient so that while the portion 33 will stand normally spaced a slight distance above the upper surface of the rail G and thus out of electrical contact therewith said portion 33 will readily yield and press into direct electrical engagement against the rail under the weight of the passing train. As soon as the train has moved off of the portion 33 said portion will again rise to its normal position out of electrical engagement with the rail.

Electric conductors 29 and 30 connect the two binding posts with the rail H and the contact arm or strip 31, and the circuits for operating the signal are substantially the same as described with respect to Fig. 4.

As many changes could be made in this construction without departing from the scope of the invention, as defined in the following claims, it is intended that all matter contained in the above description, or shown in the accompanying drawing, shall be interpreted as illustrative only and not in a limiting sense.

Having thus described my invention, what

I claim as new and desire to secure by Letters Patent is:—

1. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, the third rail being adapted to carry one side of an electric train circuit and at least one of the wheel bearing rails being adapted to carry the opposite side of said circuit, said two mentioned rails each being electrically continuous from end to end of the toy section adapted thereby for continuous propulsion of a train over said section, a contact member arranged adjacent said rails, a second contact member electrically connected with one of said rails and being movable into and out of engagement with the first contact member, means whereby the first contact member and a rail which carries the side of the circuit opposite to that carried by the rail to which the second mentioned contact member is connected may be electrically connected with opposite sides of a signal device, and means whereby to move the second contact into engagement with the first contact incident to the passage of a train along said rails.

2. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, the third rail being adapted to carry one side of an electric train circuit and at least one of the wheel bearing rails being adapted to carry the opposite side of said circuit, said two mentioned rails each being electrically continuous from end to end of the toy section adapted thereby for continuous propulsion of a train over said section, means by which to electrically connect an electrically operable device in circuit with the third rail and with the wheel bearing rail carrying the opposite side of the circuit to thereby put said electrically operable device in shunt with the track circuit, and control means for said shunt circuit comprising a relatively stationary contact, a relatively movable contact and means in addition to said rails adapted to be engaged by a passing car wheel for moving the movable contact into engagement with the stationary contact.

3. As an article of manufacture, an electric toy track section intended to be attached to or removed from track forming relation with other electric toy track sections in the

- usual manner, said section being made up of spaced wheel bearing rails and an intermediate insulated third rail with cross-tie means by which all of the rails are mechanically connected together for unitary handling, the third rail being adapted to carry one side of an electric train circuit and at least one of the wheel bearing rails being adapted to carry the opposite side of said circuit, said 5
- 10 two mentioned rails each being electrically continuous from end to end of the toy section adapted thereby for continuous propulsion of a train over said section, means by which to electrically connect an electrically operable device in circuit with the third rail and with the wheel bearing rail carrying the opposite side of the circuit to thereby put said electrically operable device in shunt with the track circuit, and control means for said 15
- 20 shunt circuit comprising a spring contact member arranged at one side of one of the rails normally out of electrical connection with said rail but being disposed to be actuated by the weight of a car part passing along said rail for being flexed into direct electrical connection with said rail.
4. As an article of manufacture, an electric toy track section intended to be attached to or removed from track forming relation with other electric toy track sections in the usual manner, said section being made 30 up of spaced wheel bearing rails and an intermediate insulated third rail with cross-tie means by which all of the rails are mechanically connected together for unitary handling, the third rail being adapted to carry one side of an electric train circuit and at least one of the wheel bearing rails being 35 adapted to carry the opposite side of said circuit, said two mentioned rails each being electrically continuous from end to end of the toy section adapted thereby for continuous propulsion of a train over said section, means by which to electrically connect an 40 electrically operable device in circuit with the third rail and with the wheel bearing rail carrying the opposite side of the circuit to thereby put said electrically operable device in shunt with the track circuit, and control means for said 45 shunt circuit comprising a spring contact member normally in "off" position but arranged to be actuated into "on" position by the flange of a car wheel passing along one of the rails of the section.
5. In a toy electric railroad, comprising spaced wheel bearing rails, an insulated power rail, and a source of electric energy connected with the power rail and with one of the wheel bearing rails, means by which to 55 electrically connect an electrically operable device in circuit with the power rail and with the mentioned wheel bearing rail to thereby put said electrically operable device in shunt with the track circuit, and a control switch included in said connecting means including a resiliently movable contact member positioned adjacent to one of said rails adapted to be moved incident to the passage of a train along the track and to effect operation of said electrically operable device as the result of said movement, and an insulating support other than the cross ties, said insulating support serving to support said contact mem-

normally in "off" position but adapted to be actuated into "on" position by a passing train, said control switch including a movable contact, and a support for said movable contact mounted upon two of said rails and serving to hold the movable contact in position to be moved by the flange of a car wheel travelling along one of the rails upon which the support is mounted.

6. In a toy electric railroad, comprising spaced wheel bearing rails, an insulated power rail, and a source of electric energy connected with the power rail and with one of the wheel bearing rails, all of said rails being electrically continuous adapted thereby for continuous propulsion of a train, a support having a pair of wire terminals thereon, conductor means providing for electrical connection between the power rail and one wire terminal, conductor means providing for electrical connection between the mentioned wheel bearing rail and the other wire terminal, and a movable switch element included in one of said conductor means movable into "on" and "off" positions incident to the uninterrupted movement of a train.

7. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the track circuit, and a control switch included in said connecting means having a spring contact part extending normally spaced above a part of one of said rails but depressible by the weight of a passing train into electrical connection with said rail part.

8. In a toy electric railroad made up of a plurality of toy track sections connected together end to end, each section comprising spaced wheel bearing rails and an insulated intermediate power rail together with cross ties extending between said rails to which the rails are attached, a source of electric energy having one side electrically connected with the power rail and having its other side electrically connected with the wheel bearing rails, connecting means by which to electrically connect an electrically operable device in circuit with the power rail and with one of the wheel bearing rails to thereby put said electrically operable device in shunt with the track circuit, said connecting means including a resiliently movable contact member positioned adjacent to one of said rails adapted to be moved incident to the passage of a train along the track and to effect operation of said electrically operable device as the result of said movement, and an insulating support other than the cross ties, said insulating support serving to support said contact mem-

ber and utilizing the power rail and at least one of the wheel bearing rails to hold the contact member spaced from the remainder of the structure.

- 5 9. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the 70
10 track circuit, and said connecting means including a movable part normally spaced from one of said rails thereby holding said shunt circuit open but said movable part being disposed to be moved into engagement with 75
15 said rail incident to passage of a train to thereby effect a closing of said shunt circuit.

10. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the track circuit, said connecting means including a movable contact movable into and out of circuit closing position, and said contact being electrically connected with one of said rails and extending to adjacent another of said rails in position to be engaged and moved into circuit closing position by a car part passing along 80
20 said second rail.

11. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the track circuit, said connecting means including a movable contact movable into and out of circuit closing position, said contact being electrically connected with one of said rails and 85
25 said contact having a member of insulating material constituting an extension thereof projecting into position to be engaged and moved by a car part passing along another of said rails thereby to move said contact into circuit closing position.

12. In a toy electric railroad, comprising spaced wheel bearing rails, an insulated power rail, and a source of electric energy connected with the power rail and with one of the wheel bearing rails, means by which 90
30

to electrically connect an electrically operable device in circuit with the power rail and with the mentioned wheel bearing rail to thereby put said electrically operable device in shunt with the track circuit, said connecting means including two contact members normally spaced apart to hold said shunt circuit open, and one of said contact members being electrically connected with one of said rails and having a springy part projecting 75
35 into position adjacent another of said rails so as to be engaged and moved into circuit closing position against the other contact by a car part passing along said second rail.

13. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the track circuit, said connecting means including two contact members normally spaced apart to hold said shunt circuit open, and one of said contact members being electrically connected with the power rail and having a springy part projecting 80
40 into position against one of the wheel bearing rails so as to be engaged and moved into circuit closing position against the other contact by the flange of a car wheel rolling along said wheel bearing rail.

14. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt with the track circuit, said connecting means including a contact member carried in insulated relation upon one of said rails and having a movable part movable into electrical engagement with said carrying rail incident to the passage of a car part along said carrying rail.

15. In a toy electric railroad, comprising spaced wheel bearing rails, an insulated power rail, and a source of electric energy connected with the power rail and with one of the wheel bearing rails, means by which to electrically connect an electrically operable device in circuit with the power rail and with the mentioned wheel bearing rail to thereby put said electrically operable device in shunt 120
45 with the track circuit, said connecting means including a contact member carried in insulated relation upon one of said wheel bearing rails and having a movable part movable into electrical engagement with said car 125
50

rying rail by being engaged by a wheel of a passing train.

16. As an article of manufacture, an electric toy track section intended to be attached 5 to or removed from track forming relation with other electric toy track sections in the usual manner, said section being made up of spaced wheel bearing rails and an intermediate insulated power rail with cross-tie 10 means by which all of the rails are mechanically connected together for unitary handling, means by which to electrically connect an electrically operable device in circuit with the power rail and one of the wheel bearing 15 rails of the section to thereby put said electrically operable device in shunt with the track circuit, and control means for said shunt circuit comprising an elongated strip 20 of material extending lengthwise of the section in the space between the power rail and one of the wheel bearing rails in position to be engaged by a car part passing along the rails of the section, and there being two separate resilient supports by which said strip 25 is mounted to be resiliently yieldable under engagement by said car part, said two supports being spaced apart one engaging each end portion of the strip and each having engagement with the adjacent end portion of 30 the section to hold the strip in operative position upon the section.

In testimony whereof I affix my signature.
L. GESSFORD HANDY.
